UNITED STATES PATENT OFFICE.

FRANK O. BRANT, OF SAN FRANCISCO, CALIFORNIA.

DISPLAY-FIGURE.

1,251,857.

Specification of Letters Patent.

Patented Jan. 1, 1918.

Application filed March 6, 1917. Serial No. 152,502.

To all whom it may concern:

Be it known that I, FRANK O. BRANT, a citizen of the United States, residing at the city and county of San Francisco and State 5 of California, have invented certain new and useful Improvements in Display-Figures, of which the following is a specification.

In the display of apparel to the public on 10 models particularly of the type of lay figures and particularly in window display, the present custom is to employ models of a given size for each different size of garment and which models are expensive owing to 15 the heads and hands and often the arms being in wax or china and considerable investment in models is required to properly display a line of garments. A model of the corresponding size is necessary for a complete 20 line of garments and to display a complete line of garments models of all sizes are required and when the garments of one size are disposed of that size of model is temporarily laid aside.

25 The present invention relates to a lay display figure formed preferably of paper or wood-board or any other suitable flat rigid material and which is capable of adjustment to the various sizes thus adapting the same 30 to the display of garments of a wide range of sizes, one having the features painted thereon preferably by the commonly used air-brush method, thus disposing of the expensive molded features of wax or china, 35 and one which is capable of adjustment to assume various poses.

The advantages of a display form of this type are numerous, the most important being, that a single form may be employed for 40 the display of garments of various sizes, the painting of the features thereon lends a life-like appearance to the model, and dispenses with the expensive wax features now employed, the adjustment of the model to various 45 poses enables garments of all types to be displayed, and the cost of construction of a form of this type is far below that of the form at present employed.

With the above mentioned and other objects in view, the invention consists in the novel construction and combination of parts hereinafter described, illustrated in the accompanying drawings and pointed out in the claims hereto appended; it being understood 55 that various changes in the form, proportion, size and minor details of construc-

tion within the scope of the claims may be resorted to without departing from the spirit or sacrificing any of the advantages of 60 the invention.

To more fully comprehend the invention, reference is directed to the accompanying drawings, wherein,

Figure 1 is a view in elevation of the preferred embodiment of my invention displaying a gown, and disclosing the support of 65 the model.

Fig. 2 is a vertical sectional view of the form removed from the stand, illustrating 70 two sections forming the same.

Fig. 3 is a view in elevation of the stand with the form removed therefrom.

Fig. 4 is a view in top plan of the stand.

Referring more particularly to the several views of the drawings wherein like characters of reference designate corresponding parts, 1 indicates the lower body portion of 75 a lay figure and 2 the upper body portion, the two portions overlapping at the waist line as at 3. The lower portion carries the 80 limbs 4 and feet 5 which may be arranged in any suitable manner, the hose and foot covering therefor being preferably painted thereon, preferably by the commonly used air-brush method. On the upper body portion is formed an integral portion 6 on 85 which is painted the head and face of the model, this being also accomplished by the air-brush method. Owing to the parts 1 and 2 being of flat material it is required that 90 the features of the model be painted thereon in order that the model will present a life-like appearance.

The arms 7 are pivotally connected as at 8 to the shoulders 9 and are capable of movement at the shoulders to assume any desired position, this construction enables arms of 95 any suitable pose to be attached to the upper body portion 2.

To properly support the model a stand or 100 support is employed, the same having a base 10 and a vertical standard 11 slotted as at 12, 13 and 14 and through which openings are adapted to pass fastening means 15, 16 and 17, the first two of which extend 105 through the lower body portion 1 of the model. The means 17 is preferably in the form of a bolt having a winged nut 18 and said bolt is adapted to project through the slotted lower ends 19 of braces 20 which are 110 pivotally connected to the upper body portion 2 through the pivotal connections 8 for

the arms, thus enabling the upper body portion 2 to be retained in any adjusted position relatively to the standard 11 to enable the bust of the model to be placed in a pose best suited to display the garment draped thereon.

On the figure is draped the gown 21, the bust and hip portions thereof being filled out as desired by the employment of paper or other padding for this purpose.

It is apparent that the adjustment of the height of the model may be readily accomplished to accommodate gowns of various lengths, the angle of rest of the upper body portion may be changed as desired as may the position of the arms, thus adapting the model to the display of gowns of various sizes and lengths and also providing a model that is capable of being manufactured at little cost.

Having thus described my invention what I claim is:

1. A lay figure for the display of wearing apparel comprising a form shaped to the contour of the human figure and comprising a standard, independent upper and lower half members of a body supported by said standard, one of said half members overlapping the other at the waist portion of said figure, means for detachably and adjustably securing the lower half body member to said standard whereby the same may be adjusted lineally thereof, and means for detachably and adjustably securing the upper half body member to said support

whereby the same may be adjusted lineally and laterally of said support and said lower half member to enable the upper half body portion of said figure to assume different positions.

2. A lay figure for the display of wearing apparel comprising a form shaped to the contour of the human figure and comprising upper and lower half detached members of a body adapted to overlap at the lower and upper portions thereof and formed of flat material, arm members formed of flat material pivotally connected to the shoulder portions of the upper half member of the body, a vertical support provided with slotted portions for sustaining the figure in given positions, adjustable attaching members for detachably connecting the lower half member of the body to said standard, adjustable body braces pivoted at one end to the shoulder portions of the upper member of the body through the pivotal connections for the arm members, said braces being slotted at their inner end portions, and adjustable means extended through the vertical support and coöperating with the slotted ends of the body braces for detachably connecting the same to said support.

In testimony whereof I have signed my name to this specification in the presence of the subscribing witness.

FRANK O. BRANT.
